US00D998872S

(12) **United States Design Patent** (10) Patent No.: **US D998,872 S**
(45) Date of Patent: **** Sep. 12, 2023**

(54) **LIGHTING DEVICE FOR IMAGING SYSTEMS WITH LIGHT PATTERN**

(71) Applicant: **Cognex Corporation**, Natick, MA (US)

(72) Inventor: **Brian Pierce**, Salem, OR (US)

(73) Assignee: **COGNEX CORPORATION**, Natick, MA (US)

(**) Term: **15 Years**

(21) Appl. No.: **29/727,864**

(22) Filed: **Mar. 13, 2020**

(57) **CLAIM**

The ornamental design for a lighting device for imaging systems with light pattern, as shown and described.

DESCRIPTION

FIGURE is a front elevation view of an ornamental design for a lighting device for imaging systems with light pattern. The ornamental design that is claimed is shown in solid lines in the drawing. The broken lines in the drawing illustrates portions of a lighting device for imaging systems with light pattern that form no part of the claimed design. Any dash-dot-dot broken lines in the drawing are included to define the boundaries of the claimed design.
